UNITED STATES PATENT OFFICE.

CLEMENT EHRET, OF WHITE PLAINS, NEW YORK, ASSIGNOR TO THE TABULATING MACHINE COMPANY, OF ENDICOTT, NEW YORK, A CORPORATION OF NEW JERSEY.

TABULATING CARD.

Application filed May 2, 1922. Serial No. 557,825.

To all whom it may concern:

Be it known that I, CLEMENT EHRET, a citizen of the United States of America, residing at White Plains, in the county of 5 Westchester and State of New York, have invented certain new and useful Improvements in Tabulating Cards, of which the following is a full, clear, and exact description.

10 In the tabulating machine art it has been the practice to utilize so-called tabulating cards or sheets which usually, for convenience in reading and punching, are provided with a number of printed amount numerals 15 or so-called index point designations on the face thereof arranged in columnar arrangement. These cards are placed in a suitable perforating machine and perforations placed therein to correspond with the data which 20 it is desired to tabulate. Thereafter these cards may be passed through sorting machines and afterwards through tabulating machines which sense the perforations in the cards and accumulate certain items and indicate or otherwise record other items which 25 are not to be accumulated. In using such cards in tabulating machines of this character, occasions sometimes arise where it is desired to effect subtracting operations. Such 30 subtracting operations can be performed upon an ordinary accumulating tabulating machine by punching the cards with the complementary numbers of the amounts to be subtracted. A group of cards including 35 such complementary punched cards may be then passed through the tabulating machine and the net result displayed at the end of the run will be an accumulation of all non-complementary perforations less the total 40 of the amounts whose complements are perforated in said complementary cards. In this way subtracting operations can be performed without in any way changing the design or mode of operation of the tabulating 45 machines themselves which are adapted primarily for arithmetical accumulating or adding purposes.

The use of these complementary cards has become quite general in this art, but difficulties have been encountered in that complementary cards are difficult to read and check, and their use has therefore led to occasional errors. To eliminate this difficulty in checking complementary cards, various expedients

have been resorted to. Some of these expedients have necessitated the reversal and turning over of the complementary cards relative to the other cards in a group to view and tabulate the same for complementary readings and such cards further required a modification in the tabulating machine when using such reverse cards. 55

The present invention has for its object the provision of a tabulating card upon which either accumulative data or data to be subtracted or both can be perforated and in which the data to be subtracted can be read directly from the card without the necessity of involved mental computations upon the part of the operator and without 60 the necessity of reversing or turning the card in viewing and tabulating complementary quantities. 65

Referring to the drawings, a typical embodiment of a tabulating card embodying my invention is illustrated. As shown, the card comprises a number of fields 10, 11, 12, 13, etc., containing the usual index point printed designations 14 and having the numbers increasing in value from the top to the bottom of the card. As thus far described, this is the customary and well known arrangement of a Hollerith tabulating card. Any desired amounts can be perforated in these various fields to designate different 70 classes of data which are desired to be tabulated. Certain data can be accumulated and other data may merely be read without 75 accumulating. 80

In accordance with my invention there are disposed at any desired position on the card the so-called complementary fields 15 and 16. Any number of these fields may be provided. As shown, there is a field 13 for 85 accumulating quantities and a corresponding complementary quantity field. There is also provided an amount field 12 and a corresponding amount complement field 16. 90

It will be noted that the index point printed designations 14^b on the two complementary fields are arranged in reverse order to those in the accumulative fields. These printed designations in the complementary fields begin with 9 at the top and successively descend by units to zero at the bottom of the card. This arrangement of the complementary designations permits the user to visually read the direct number of 95 100 105

which a complement is printed. For example, suppose the operator desires to subtract the number 96430. The first step is to subtract mentally one unit from the right hand column of the figure and punch the resulting amount, i. e., 96429 in field 15. By comparison with the similarly located printed designations in the accumulating or adding fields 12 and 13, it will be seen that the 10 perforations of field 15 in their location on the card designate a direct amount of 03570. This latter number is the complement of the amount which was initially to be subtracted, thus—

15	000000
	number 96430
	complement 03570

20 Therefore the card arrangement is such that the visual reading is that of the direct number decreased by one in the right hand column whereas the punched hole location is that of the complementary number. Inasmuch as the location of the punched index point perforations controls in the operation of the card in the tabulating machine, there will be an adding of the complementary quantity which, in effect, is the same as the 25 subtracting of a real quantity. The operator of the machine in punching and comparing the cards can readily check the amounts since there is no necessity of going through a mental subtracting operation.

30 The dual card described provides for both accumulating operations and subtracting operations. The tabulating machine can be set to add up all of the items in the accumulative field and to subtract all of the amounts 35 visually shown in the complementary fields from the amount standing upon the various tabulating counters at the beginning of an operation. This will give net balances. Amounts can be added to the balance from 40 which subtractions are made by merely running an accumulating card through the machine and adding the amounts to the counter from which subtractions are being made.

Other uses of the dual card will be readily apparent to those skilled in the art.

What I claim is—

1. A tabulating record sheet having index point printed designations on one side thereof, disposed in a complementary manner to the relative and corresponding perforated index point locations as viewed from the same side of the sheet.

2. A tabulating record sheet having index point printed designations thereof so related to one edge of the sheet that they are complementary in the value of the corresponding perforated index point locations relative to the same edge of the sheet as viewed from the same side of the sheet.

3. A tabulating record sheet comprising a plurality of numeral bearing printed fields, the index point printed designations of certain of said fields being arranged in increasing order from the top to the bottom and the index point printed designations of other of the fields being arranged in a complementary manner to the index points of the first mentioned fields as viewed from the same side of the sheet for the purpose described.

4. A tabulating card having a field adapted to be perforated and when perforated to be fed to a tabulating machine to cause the accumulation of a number corresponding to the relation of the perforations with respect to one of the faces of the card and means upon the same face of the card for indicating the complement of the number corresponding to the particular perforations.

5. A tabulating card having a field adapted to be perforated and when perforated to be fed to a tabulating machine to cause the accumulation of a number corresponding to the perforations, and means upon that face of the card which leads, when the card is presented to the tabulating machine for data accumulation, for indicating the complement of the number corresponding to the perforations.

In testimony whereof I hereto affix my signature.

CLEMENT EHRET.
